Application March 31, 1948, Serial No. 18,188

15 Claims. (Cl. 123—119)

1

This invention relates to improvements in charge forming devices or carburetors for engines.

It has heretofore been proposed to incorporate in fuel feeding systems for engines, particularly aircraft engines, means which tend to prevent or reduce the tendency towards detonation by enriching the fuel-air mixture as a function of manifold pressure and temperature when the engine is subjected to extremely heavy loads, as for example, during take-off and emergency power settings. Such devices, however, have lacked the necessary accuracy for maximum economy, have been difficult to adjust and for engines of certain characteristics the temperature response may be so slow as to result in too lean a mixture at the beginning of acceleration in the high power range.

An object of the present invention, therefore, is to provide in a carburetor or fuel metering device improved means for automatically producing enrichment of the fuel-air mixture as a function of manifold pressure and temperature. More specifically, the invention aims to provide in a fuel feeding system for engines metering means responsive to manifold pressure and temperature having improved characteristics with respect to accuracy, facility of adjustment and overcoming temperature lag.

Another object is to provide in a force feed or injection carburetor automatically operative manifold pressure and temperature responsive enrichment devices which may be readily adapted to the normal metering system.

The foregoing and other objects and advantages will become apparent in view of the following description taken in conjunction with the drawings, wherein:

Figure 1 is a schematic in section and elevation of an injection carburetor constructed in accordance with the present invention;

Figure 2 is an enlarged sectional schematic of the fuel control body portion of the carburetor; and

Figure 3 is a fragmentary view of part of the control section of the carburetor, showing a modification in structure.

Referring to the drawings, a main air intake conduit 10 leads to the supercharger 11 of an internal combustion engine generally indicated at 12. The conduit 10 is controlled by a pair of throttles 13 operable from the pilot's cockpit in a known manner, and anterior the throttles is the carburetor 17 including a large venturi 14 and a pair of boost venturis 15. In the type

5 of fuel supply system used to illustrate the present invention, the pilot controls the air supply by manipulating the throttles 13, while the metered liquid fuel is discharged under pressure into a supercharger slinger ring by means of a fuel discharge nozzle generally indicated at 16. It will be understood, however, that the nozzle 16, instead of discharging into the air intake system in the manner shown, could be a series 10 of nozzles discharging directly into the individual engine cylinders as in the case of direct injection fuel feeding systems, or the nozzle could constitute part of a pressure feed system for a gas turbine or any other type of power plant to which it may be adapted.

15 The fuel metering apparatus or carburetor 17 comprises two main sections, namely a fuel regulator section generally indicated at 18 and a fuel control body or section indicated at 19. The regulator section or unit comprises a fuel valve 21 shown as of the poppet type and arranged to slide in a valve body 22 mounted in a supporting boss 23 and formed with a series of inlet ports 24. Fuel is supplied to the ports 24 by way of a 20 conduit 25, float chamber 26, strainer 27, strainer chamber 28 and conduit 29. The fuel is preferably maintained under a substantially constant pressure, for example 17 p. s. i., by means such as a conventional fuel pump, not shown. The poppet valve 21 is carried by an air diaphragm 30 and a fuel diaphragm 31, which have their respective outer edges clamped between adjacent housing sections and their central portions clamped between a series of bushings removably 25 secured on the stem 32 of the poppet valve 21. These diaphragms, together with a rigid partition 33 and a central sealing diaphragm 34, divide the interior of the regulator 18 at this point into a series of chambers, viz. air differential 30 chambers A and B, and fuel differential chambers C and D. Chamber A is subjected to a measure of carburetor air intake pressure by means of a series of impact tubes 36, which have their entrance or intake ends located adjacent 35 the carburetor deck and communicate with chamber A by way of annular chamber 37, valve port 38 and passage 39. Chamber B is subjected to Venturi suction by means of an annular channel or chamber 40 formed around the throat of each of the small or boost venturis 15, passage 41 and branch passages 42, 42'. Chambers C and D are subjected respectively to metered and unmetered fuel pressure. The small diaphragms 43 and 43' serve the purpose of balancing the regulator system including the poppet valve 21, the

diaphragm 43 constituting the movable wall of a chamber 44 to which unmetered fuel under pressure is communicated by way of restricted channel 45. Another channel 46 serves to communicate accelerator pump fuel pressure to chamber 44 from accelerator pump 47, so that when the throttles 13 are suddenly opened, the pressure in chamber 44 is increased and the poppet valve 21 moved toward open position to increase the head across the metering jets for acceleration purposes.

The air chambers A and B are interconnected across the diaphragm 30 by a small passage 50 having bleeds 50' therein; and port 38 in the air passage 39 is varied as a function of altitude or changes in density by a valve 51 operatively connected to the movable end of a sealed corrugated bellows 52 which is mounted in a housing 53 open to the air intake conduit 10. The bellows 52 is loaded in a manner such as to render it responsive to changes in both pressure and temperature (see Patent No. 2,376,711 to Frank C. Mock), and is, therefore, responsive to changes in density. At relatively high barometric pressures, as for example, those prevailing at sea level, the bellows tends to collapse, causing valve 51 to increase the area of port 38, and increase the flow of air through passage 39, while at relatively low barometric pressures, as for example, those prevailing at high altitudes, the bellows tends to expand and cause the valve 51 to decrease the area of the port 38 and restrict the flow of air through the passage 39. As the passage 39 becomes more and more restricted, the differential across the air diaphragm is reduced, tending to reduce travel of the poppet valve 21 for a given change in throttle position. By this means the fuel-air ratio is maintained at a predetermined value irrespective of changes in altitude.

The particular construction of the regulator section of the carburetor forms no part of the present invention; it is shown for the purpose of presenting in combination with the control section of the carburetor a self-supporting disclosure.

The fuel control section 19 of the carburetor contains the metering jets and coating control valves, and it is in this part of the carburetor that the improved manifold pressure and temperature responsive devices of the present invention are located.

Unmetered fuel from chamber D of the regulator section flows to the control section by way of a passage 60. In the diagrammatic or schematic illustration of Figure 2, this passage 60 has branches 61 and 62 leading therefrom. The branch 61 contains a metering jet 63, commonly termed the "automatic lean" metering jet since this jet meters a relatively lean fuel-air mixture particularly adapted for low power settings. Beyond the jet 63, the branch passage 61 opens into a chamber or passage 64, from which fuel flows through port 65 controlled by a manual mixture control valve 66 into chamber 67 and thence by way of metered fuel conduit 68 to the discharge nozzle 16. The manual mixture control valve is provided with a handle or lever 66' which may be suitably controlled from the pilot's compartment; it also includes a ported, disc-shaped, rotatable valve member 66'' which in addition to the port 65, is formed with a port 69 adapted to selectively communicate a flow passage 70 with the chamber 67. In this passage 70 is another metering jet 70', commonly termed the "auto-rich" jet since when the flow through this jet is added to that through jet 63, the fuel-air ratio

becomes sufficiently rich for most normal cruise conditions.

The fuel flowing through branch passage 62 may flow through either one or both parallel passages 71 or 72 and ports 77 and 83 (which latter are controlled by separate pressure and temperature responsive valves 79 and 85), and thence by way of passage 73, port 74, chamber 75, passage 76, chamber 64, port 65 and conduit 68 to the discharge nozzle 16.

Valve port 77 is defined by a seat member 78 and is controlled by contoured needle valve 79 connected to the movable end of a pressure responsive element such as bellows 80 located in a chamber 81, to which manifold pressure may be communicated by way of a passage or conduit 82.

Valve port 83 is defined by a seat 84 and is controlled by contoured needle valve 85 having a stem slidingly mounted in a guide 86. This valve 85 is controlled primarily by a temperature responsive element such as a bellows 87 located in a chamber 88 and loaded with a suitable fluid medium. A temperature element 89 is preferably positioned in the engine intake manifold. It may be of any suitable type; in the form herein illustrated it is operatively connected with the interior of the bellows 87 by way of a capillary tube 90. As will be understood, when the thermal element 89 becomes heated, the fluid in the line 90 and bellows 87 expands, thereby expanding the bellows. The movable end of said bellows is in abutting engagement with a contact head 91 formed on the end of the stem of valve 85, said stem being encircled by a spring 92 which engages a thrust collar 93 secured on said stem, so that the valve 85 is normally biased towards closed position and is opened in response to expansion movement of the bellows 87.

In order to insure prompt response of the temperature needle or valve 85 when the manifold pressure and temperature is suddenly increased, as by an opening movement of the throttles 13 and/or an increase in supercharger output, a so-called "temperature anticipator" generally indicated at 94 is provided; it comprises a diaphragm 94' having its central portion clamped or engaged between flanged stiffening and guide plates 95 and 96 and its peripheral edge portion clamped between inner and outer casing sections 97 and 98, which together with said diaphragm define a pair of pressure chambers 99 and 100. The diaphragm 94' is operatively connected to the valve 85 by means of a rod 101, link 102, lever 103 pivoted or fulcrumed at 104, and yoke or fork 105 formed on the lower end of said lever. A spring 106 normally urges the diaphragm 94 and interconnecting linkage in a direction permitting the spring 92 to close the valve 85.

Manifold pressure is communicated to the chamber 99 by way of chamber 81 and port 107, while at the same time manifold pressure may be also communicated to chamber 100 by way of chamber 81 and control bleed 108.

It will be seen that when there is a sudden increase in manifold pressure in the chamber 81, there will be a corresponding increase in the chamber 99, the result of which is to cause the diaphragm 94' to move to the left and suddenly open the valve 85 until the pressure equalizes in the chambers 99 and 100 due to the action of the bleed 108, whereupon the diaphragm 94 will move back to its neutral position. By this time the temperature element 89 and associated bellows 87 will have stabilized and have become effective to control the valve 85. The length of time required for the diaphragm 94' to move back and

free the valve 85 may be predetermined by the capacity of the control bleed 108, which is made a function of the rate of response of the temperature control. An adjustable contact 109 limits the maximum travel of lever 103 in a valve opening direction.

The port 14 is defined by a valve seat 111 in which an enrichment control valve 112 is mounted, said valve being provided with a stem 112' encircled by a spring 113 adapted to normally urge or bias the valve towards closed position. This valve 112 is controlled by diaphragm 115 clamped at its central portion between a pair of flanged stiffening and guide plates 116 and 117, the said diaphragm in conjunction with the surrounding walls defining chambers 115 and 118. Unmetered fuel under pressure is communicated to the chamber 118 by way of passage 119, and when the metering head as determined by the pressure of the unmetered fuel reaches a predetermined value, the valve 112 opens and permits fuel to flow from passage 73 to passage 16 and thence to the discharge nozzle 16 by way of chamber 64, port 65 and passage 68. Since the metering head varies in direct relation to the flow of air through the carburetor, the valve 112 may be set to open only when the air flow attains a predetermined value. Since the valve 112 is in series with the valves 79 and 84, it determines the point of enrichment on the power curve as a function of mass flow of air through the carburetor; it prevents an over-rich mixture in case of low air flows and relatively high manifold pressures which prevail during certain operating conditions, as for example, where during cruising the engine propeller is set at a high pitch with the throttles wide open and which will increase the load on the engine so that it slows down, whereupon there is a low drop across the carburetor with a relatively high supercharger output.

A power enrichment jet 120 is located in passage 62; it has a flow capacity sufficient to handle maximum enrichment flows.

An idle valve is indicated at 121; it controls a port 122 and is connected by suitable linkage in a known manner to the throttles 13 to be operated when the latter are initially opened and meter idling fuel. When the idle valve reaches a fully open position, metering is taken over by the respective metering jets in accordance with the position of the mixture control valve 66.

The valve indicated at 123 is a so-called fill valve; its purpose is to allow chamber C of the regulator to fill with fuel when the carburetor has been empty. It is held open in all manual mixture control positions of valve 66 except idle cut-off by a cam on the inner end of the valve shaft.

The valve indicated at 125 is a derichment valve for use when an antidentalant system is operatively associated with the carburetor; it controls flow of fuel to and through a derichment jet 126.

The passage indicated at 127 is for venting chamber C of the regulator to the discharge conduit 68.

Operation

When the engine is running, air is drawn into the air intake conduit 10 and through the small or boost venturis 15 and main venturi 14, and a differential pressure is created between the throats of the small venturi and the air intake which at constant entering density is proportional to the square of the quantity of air flowing. These respective pressures are transmitted to

chambers A and B of the fuel regulator unit on opposite sides of the air diaphragm 30 and create a net force on said diaphragm tending to open the fuel or poppet valve 21, this force usually being termed the "air metering force." If this force were unopposed, the fuel or poppet valve 21 would tend to move to full open position; but when the valve opens, fuel under pressure flows into unmetered fuel chamber D and through conduit 60 to the fuel control section or body, where it flows through any one or more of the respective metering orifices, depending upon the position of the manual control valve 66, and thence to the discharge conduit 68 and discharge nozzle 16, from which it is discharged under pressure into the air stream flowing to the engine. Chamber D is subjected to unmetered fuel pressure and chamber C to metered fuel pressure, and the differential between these respective pressures acts on the diaphragm 31, tending to move the poppet valve 21 to the left or in a direction to close the valve. This force is commonly termed the "fuel metering force" and it opposes the air metering force. The valve 21 is thus caused to adjust itself to a point of equilibrium such that the differential pressure across the fuel metering orifices, or the metering head, is equal to the differential between the air inlet and the venturi, and in this manner, substantially constant fuel-air proportioning is maintained. As engine speed is decreased, the rate of air flowing through the venturis is decreased, thereby decreasing the differential pressure acting on the diaphragm 25, causing the valve 21 to move towards closed position and decrease the fuel flow to compensate for decreased air flow. Since the venturi-to-air scoop differential pressure increases upon a decrease in entering air density, the differential pressure across the diaphragm 30 will tend to increase, thereby increasing the fuel flow and enriching the fuel mixture upon a gain in altitude. The automatic control unit, including the bellows 52, coacts with the calibrated bleed 50' to prevent such enrichment, said bleed being substantially ineffective to vary the differential pressure in chambers A and B and across the air diaphragm 30 at such times when the needle valve 51 is in open position, as at ground level, but becoming increasingly effective in reducing the differential pressure as said needle progressively restricts the port 38 and consequently the passage 39 with increase in altitude. Thus, for any given mass air flow, the needle 51 will so restrict the passage 39 with variations in altitude that the differential pressure in chambers A and B will remain constant notwithstanding the fact that the differential in pressure at the venturis 15 and the impact tubes 36 increases with a decrease in entering air density.

Coming now to the operation of the improved manifold pressure and temperature responsive devices of the present invention, let it be assumed that the manual mixture control valve 66 has been turned to a position where fuel may flow to the discharge nozzle 16 through the passages or channels 64, 70 and 76 (which would be the position shown in Figure 2 where both ports 65 and 69 are open). Under these conditions, should the engine power control lever (not shown) be advanced to a point where, for example, take-off power is attained and which would necessitate a relatively high engine speed at the usual propeller pitch setting, then (1) the metering head would immediately increase to a value such that the fuel pressure in chamber 118 acting on the dia-

phragm 115 would cause the valve 112 to open; (2) the build-up in manifold pressure would be communicated to the chamber 81, causing the bellows 80 to collapse and open the valve 79; (3) this manifold pressure in chamber 81 would immediately be communicated to chamber 99 where it would act on the diaphragm 94', tending to move the latter to the left, opening the temperature needle valve 85 to a predetermined metering position as determined by control bleed 108 and holding the said valve open until the pressure entering through the control bleed 108 equalized the pressure in the chambers 99 and 108, and (4) there would be an increase in manifold temperature which would cause the bellows 87 to expand so that by the time the "anticipator" diaphragm 94' had released the valve 85, the temperature element 89 and bellows 87 would have stabilized and have taken over the metering control of valve 85.

The function of the enrichment valve 112 and that of the manifold pressure valve 79 overlap to a certain extent. Thus, the valve 112 meters as a function of mass flow of air to the engine as registered in the carburetor Venturi system and transmitted to the enrichment valve diaphragm 115 in terms of fuel metering head, and under certain operating conditions this is a substantially true index of manifold pressure. However, this is not the case under all operating conditions, since factors such as propeller pitch, throttle position and altitude may produce a drop across the carburetor which could not be used as an index of manifold pressure. Furthermore, when the valve 112 is used alone, it must take care of such a wide range of manifold pressures and temperatures as to make it extremely difficult to set the valve so that it will give the most economical or best power mixture in all ranges, and the net result must be a compromise. By utilizing the valve 112 in series with parallel pressure and temperature controls, it will prevent enrichment at manifold pressures which are relatively high and yet not dangerously so, while at the same time the flow through the carburetor is relatively low. Invariably, when dangerous manifold pressures and temperatures are approached, the metering head has risen sufficiently to insure opening of valve 112. Once this valve opens, enrichment becomes a function of manifold pressure and temperature and may be accurately regulated since there are separate or individual pressure and temperature controls.

Figure 3

In Figure 3, a modification is shown wherein a separate manifold pressure valve is dispensed with and a temperature responsive control is coordinated with the metering head valve 112. In this instance, parts which are of identical construction with those shown in Figure 2 are given similar reference characters and hence require no further explanation. The temperature responsive bellows or element 87 in this instance is provided with a link 130 at its movable end which is pivotally connected at 131 to a lever 132, the latter at its upper end having a loose or shiftable pivotal connection by means of a slot 133 with the rod 101 of the "anticipator" diaphragm 94'. At its opposite end, the lever 132 is operatively connected to the metering head valve 112 by means of an adjustable contact 134 and compression spring 135 of such strength or spring rate as will permit the valve 112 to open when the fuel metering head attains a predetermined value.

If it be assumed that the engine power control lever has been advanced to a setting calling for high take-off or emergency power, then the metering head or unmetered fuel pressure in chamber 118 will attain a value such as will open the valve 112 and permit fuel to flow from passage 62 and chamber 75 (heretofore described in connection with Figure 2) through port 74 to passage 76, and thence by way of passage 64 of Figure 2, port 65 and passage or conduit 68 to the discharge nozzle 16 of Figure 1. As the manifold pressure increases, there will be a corresponding increase in temperature, and immediately upon an increase in manifold pressure, the anticipator 94 becomes operative, the pressure in chamber 99 increasing and causing the diaphragm 94' to move to the left and relieve the pressure on spring 135, whereupon the valve 112 will further open to enrich the fuel mixture. The action of the anticipator will be only momentary, depending upon the capacity of the control bleed 108 and which is preferably chosen or calibrated as a function of the rate of response of the temperature bellows 87. Thus, as soon as the temperature element 89 and bellows 87 stabilize, the diaphragm 94' will move back and the temperature control will take over metering of the enrichment fuel. Since manifold temperature is a function of manifold pressure, and since also excessively high temperatures are conducive to detonation, an effective metering of enrichment fuel may be obtained.

Although only two embodiments of the invention have been illustrated and described, various changes in the form and relative arrangement of the parts may be made to suit requirements.

We claim:

1. In a fuel metering device for an engine having an intake manifold, fuel metering means adapted to maintain a predetermined normal ratio of fuel-to-air, independently operable valves arranged in parallel and adapted to meter supplementary fuel to the normal supply under high charge pressure and temperature conditions, an element responsive to changes in manifold pressure for controlling one of said valves and another element responsive to changes in manifold temperature for controlling the other of said valves.
2. In a fuel metering device for an engine having an air intake system including an intake manifold, fuel metering means for maintaining a predetermined normal ratio of fuel-to-air, a pair of valves arranged in parallel for metering supplementary fuel to the normal supply under abnormally high charge pressure and temperature conditions, an element responsive to changes in manifold pressure for controlling one of said valves and another element responsive to changes in manifold temperature for controlling the other of said valves, the other of said valves, a third valve arranged in series with said pressure and temperature valves for determining the point on the power curve at which said latter valves become effective to meter fuel to the normal supply, and means responsive to a function of the air intake system for controlling said third valve.
3. In a fuel metering device for an engine having an air intake system including an intake manifold, fuel metering means for maintaining a predetermined normal ratio of fuel-to-air including a plurality of metering jets and means responsive to changes in mass flow of air to the engine for establishing a metering head across said jets, a pair of independently operable valves for metering supplementary fuel to the engine

under abnormally high charge pressure and temperature conditions, a flexible element responsive to changes in intake manifold pressure for controlling one of said valves and another element responsive to changes in manifold temperature for controlling the other of said valves, a third valve in series with said pressure and temperature valves for determining the point on the power curve when said latter valves become effective to meter fuel to the normal supply, and means responsive to the fuel metering head for controlling said third valve.

4. In a fuel metering system for an engine, a fuel control valve, means responsive to changes in temperature of the air flowing to the engine for controlling said valve, means responsive to changes in an engine condition operatively connected to said valve and arranged to initially move said valve toward open position to avoid delay due to lag in temperature response of said first-named means, and means rendering said condition-responsive means ineffective immediately following initiation of valve opening movement.

5. In a fuel metering system for an engine, a fuel control valve, means responsive to changes in temperature of the air flowing to the engine for controlling said valve, means responsive to changes in the rate of flow of the air flowing to the engine adapted to initially move said valve toward open position prior to said temperature responsive means becoming effective to control the valve, and means rendering said second-named means ineffective to control said valve upon said temperature responsive means becoming effective to control the valve.

6. In a fuel metering system for an engine, a valve, pressure responsive means for controlling said valve, means responsive to changes in temperature of the air flowing to the engine for actuating said valve, means responsive to changes in an engine condition adapted to initially act on said pressure responsive means when the engine is accelerated and move the valve toward open position to avoid lag due to delay in temperature response, and means for rendering said condition-responsive means ineffective to act on said pressure-responsive means immediately following opening movement of said valve.

7. In a fuel metering system for an engine provided with a power control device, a valve, a pressure responsive element connected to said valve for controlling the latter, means responsive to changes in temperature of the air flowing to the engine for controlling said valve, means defining a pair of pressure chambers on opposite sides of said element, means becoming effective upon an increase in power for automatically establishing a differential pressure across said element in a direction tending to open the valve, and means for automatically nullifying said differential when said temperature responsive means becomes effective to properly locate said valve.

8. In a system as claimed in claim 7, wherein said last named means includes a control bleed calibrated to determine the period of time over which said differential remains effective to control said valve.

9. In a fuel metering system for an engine provided with a power control device, a fuel control valve, means responsive to changes in temperature of the air flowing to the engine for controlling said valve, a pressure responsive element connected to said valve, means becoming effec-

tive upon an increase in power for subjecting said element to a differential pressure as a function of the rate of change of flow of the air flowing to the engine for initially moving said valve toward open position to avoid lag due to delay in temperature response, and means for automatically determining the period of time over which said differential remains effective.

10. In a system as claimed in claim 9, wherein said pressure responsive element comprises a diaphragm and means defining a pair of pressure chambers on opposite sides of the diaphragm, and means for automatically subjecting said chambers to engine manifold differential pressures upon an increase in power to cause the diaphragm to act on said valve in a direction tending to open the latter.

11. In a pressure feed carburetor having fuel regulator and control sections, said control section being provided with a plurality of metering jets including a power enrichment jet and said regulator section being provided with a fuel control valve and means responsive to a differential pressure varying with the mass flow of air and fuel to the engine for controlling said valve to maintain a metering head across said jets, a pair of valves arranged in parallel in said control section for enriching the normal fuel mixture under high manifold pressure and temperature conditions, an element responsive to changes in manifold pressure for controlling one of said parallel valves and another element responsive to changes in manifold temperature for controlling the other of said parallel valves, a power enrichment valve arranged in series with said parallel pressure and temperature valves for determining the point on the power curve at which said latter valves become effective to enrich the normal fuel charge, and means responsive to the metering head for controlling said power enrichment valve.

12. In a fuel metering device for an engine having an air intake system including an intake manifold, fuel metering means including one or more metering jets and means operating as a function of the flow of air and fuel to the engine for maintaining a metering head across said jets, a power enrichment valve for enriching the normal fuel charge at a predetermined point in the power curve, means operating as a function of the flow of air to the engine for controlling said power enrichment valve, and means responsive to changes in manifold temperature arranged to control said power enrichment valve in conjunction with said first-named control means.

13. In a fuel metering device for an engine having an air intake system including an intake manifold, fuel metering means including a plurality of metering jets, means for maintaining a metering head across said jets as a function of the mass flow of air and fuel to the engine, a power enrichment valve, means responsive to the metering head for controlling said latter valve, means responsive to changes in engine manifold temperature also connected to said power enrichment valve for controlling the latter, and means responsive to the rate of change in manifold pressure for modifying the action of said temperature control.

14. In a fuel metering device for an engine having an air intake system including an intake manifold, fuel metering means including a plurality of metering jets, means for maintaining a metering head across said jets as a function of

the mass flow of air and fuel to the engine, a power enrichment valve, means responsive to the metering head arranged to open said valve when the metering head attains a predetermined value, a temperature responsive element also operatively connected to said valve and arranged to modify the action of the latter as a function of manifold temperature, and means responsive to the rate of change in manifold pressure operatively connected to said enrichment valve and arranged to momentarily move the latter toward open position upon an increase in manifold pressure to avoid delay due to lag in temperature response. 10

15. In a fuel metering device for an engine, a fuel enrichment valve, means responsive to changes in engine manifold temperature having an operative connection with said valve, and means responsive to a differential pressure de-

pendent upon the rate of change in the flow of air to the engine arranged to momentarily enrich the fuel as a function of air pressure to avoid delay due to lag in the operation of said temperature responsive means. 5
